UNITED STATES PATENT OFFICE

WOLF KRITCHEVSKY AND HAROLD C. PRUTSMAN, OF CHICAGO, ILLINOIS, ASSIGNEES
TO RIT PRODUCTS CORPORATION, OF CHICAGO, ILLINOIS, A CORPORATION OF DELA-
WARE

FABRIC STRIPPER

No Drawing.

Application filed April 30, 1930. Serial No. 448,784.

Our invention relates to a composition of matter intended for use as a color remover or stripper for dyed fabrics.

Due to the extensive practice of this art, both commercially and in households, there is a large and growing demand for a product that will accomplish the desired result in a satisfactory manner. The class of chemicals most generally used for this purpose is 10 that known as sulphites, hydrosulphites and sulphoxylates. A most commonly used composition consists of a mixture of zinc dust and sodium bisulphite which, in a water solution, evolves hydrogen and 15 forms a chemical known as zinc hydrosulphite. A well known chemical of this class is sodium hydrosulphite of the general formula $\text{Na}_2\text{S}_2\text{O}_4$ known commercially in this country as lykopon, bleacan, decrolin, etc. 20 This chemical when boiled in water either alone or in the presence of an alkali or acid evolves hydrogen according to the formula or equation:

this substance is sold in large quantities for stripping dyes and for reducing vat dyes in dyeing and tinting. The chemical is quite efficient, but is very unstable due to its capacity of absorbing oxygen and moisture from 30 the air, resulting in liberation of hydrogen. It is therefore necessary that the product be sold in sealed containers and that it be used promptly by the purchaser.

35 Many attempts have been made to obviate this difficulty and stabilize the substance. In one instance the sodium hydrosulphite is combined with formaldehyde resulting in the formation of sodium hydrosulphite formaldehyde, otherwise known as sodium sulphoxylate. This product is somewhat more stable than hydrosulphite alone but it is not stable in a practical sense.

40 Another method of effecting stabilization is to form normal zinc salts known as zinc hydrosulphites or protoline or zinc sulphoxylate hydrosulphite. These represent an improvement over lykopon but it is not stable and must be isolated from air and moisture.

50 In view of the fact that all of the sub-

stances heretofore mentioned are water soluble, it has been proposed that a desired result might be secured by forming the insoluble derivatives, and zinc salts, known as basic zinc sulphoxylate hydrosulphite has 55 been developed, otherwise known as "rongalite" or "formopon-extra". The substances are considerably more stable in air, due to the fact that they are insoluble in water. However, in order to use them they must be 60 combined in an acid solution to neutralize the zinc salt and liberate the free acid. The result is a compound much weaker than straight sodium hydrosulphite. However, even these derivatives are not stable for indefinite 65 periods in open air.

In order to merchandise a package product for household use it is difficult, if not impossible, to provide hermetic sealing. For that reason, we have for some years marketed a 70 product under Patent No. 1,524,737 consisting of a mixture of a hydrosulphite and a solid acid-reacting substance. This product is an improvement over the art, but still not entirely satisfactory. It is for this reason 75 that we have carried on a series of experiments looking toward the development of a stripping substance that could be marketed in package form and that would be stable under 80 all atmospheric conditions.

As the result of our experiments, we have 85 found that the main reason for the decomposition of the hydrosulphite compounds was that the substance is hygroscopic and decomposes in the presence of air and moisture. We have, therefore, determined that if the 90 hydrosulphite particles are enveloped in a water-proof or water-resistant film, the oxygen of the air and moisture will be excluded and the substance will remain stable indefinitely.

In speaking of hydrosulphites, we include 95 under that name all compounds that belong to this class. It may include the salts of hydrosulfurous acid of the general formula

It also may include the different salts of 100 the condensation product hydrosulfurous

acid, or its salts with formaldehyde which have the following formula

5

known as formaldehyde sulfoxalic acid and its salts whether sodium, zinc, calcium, etc. and formaldehyde bisulfuric acid and its salts, the formula being

10

15

or mixtures thereof. These compounds are technically known as lykopon, which is sodium hydrosulphite, decrolin or protolin which is zinc hydrosulphite-sulphoxylate, or formopon which is sodium sulphoxylate formaldehyde or basic zinc sulphoxylate formaldehyde, technically known as Formopon-extra,

20

Rongalite, etc.

There are many other formulæ and many other technical names but for brevity the substances are herein called hydrosulphites, as they belong generally to the hydrosulfite 25 class, the hypothetical hydrosulfurous acid being the parent substance of the whole class.

We have found that when sodium hydrosulphite or one of the derivatives heretofore mentioned is intimately mixed with an oily 30 substance, the product will remain stable even when it is exposed to the air for practically an indefinite period. An oily substance that will accomplish this result may be a hydrocarbon such as petrolatum, kerosene, or paraffine, or a metallic soap that is insoluble in water, such as aluminum stearate or even an ordinary anhydrous soap, such as sodium stearate, or a sulphonated soap or a vegetable oil, such as castor oil, corn oil, or a sulphonated oil, or a fatty acid like oleic acid, stearic acid, sulphonated fatty acid, or a naphthenic acid or a sulphonated petroleum residue, etc.

We have determined that when a quality 35 of any of the mentioned oily substances varying from 2½% to 5% and up of the total amount of hydrosulphite, depending on the character of the oily substance, is intimately mixed therewith, an oily film is formed around each particle of the hydrosulphite, thus providing an encasing envelope that 40 serves to exclude air and moisture for practically an indefinite period.

A product such as described can be used in that form in operations where an aqueous solution is not necessary. In cases where the enveloping oily water-resistant film is soap or a sulfonated soap, the product could be used in water without any other chemicals, as the water resistant but soluble film will dissolve in excess of water and liberate the hydrosulphite for action.

Or it may be merchandised in that form for household use in a water solution with instructions to the user to supply to the solution an agent that will serve to act on the oily

substance and release it from its intimate association with the hydrosulphite. This will permit the hydrosulphite to enter into solution and to act in the expected manner.

An agent that will act as required may consist of a saponifying substance such as an alkali like caustic soda, caustic potash, soda ash, borax, dry sodium phosphate, or ammonia, or derivatives that are suitable to form a soluble soap with a free fatty acid or a saponifiable oil; or an emulsifying substance such as ordinary soap, the selection of the agent depending on the character of the oily substance employed for enveloping the stripping chemical.

70

In the use of these agents the oily substance is freed from the hydrosulphite and permitted to enter into solution or suspension. In the use of the saponifying agent, particularly where an excess of alkali is used, there will be formed an alkaline solution that will assist in the stripping action.

80

We may prefer to also add to the solid compound other substances such as solvents, assistants, penetrators, and fillers, so long as any such added substance does not interfere with the function of the oily substance.

85

In order to exemplify our invention, we shall cite a few compositions of matter that we suggest for use.

95

60 parts of sodium hydrosulphite are intimately mixed thoroughly with 40 parts of sulphonated oil or sulphonated soap until the oily film thoroughly envelopes the hydrosulphite and thereby excludes it from air and moisture. This product could be used as such, or mixed with a diluent or assistant like salt, sugar, etc., to turn it into a solid mass which could be granulated or pressed into cakes.

100

This product will keep for a long time under ordinary climatic conditions without any deterioration, and in order to be used it has to be used in an excess of water, which water will dissolve the moisture-resistant, but water-soluble film and liberate the hydrosulphite for action.

110

Another example of a composition of matter that would be within the spirit of this invention is as follows: 30 parts of neutral zinc sulfoxalate formaldehyde are enveloped with 30 parts of petrolatum until the oily film surrounds the chemical thoroughly and protects it from the excess of moisture. Then the paste is mixed thoroughly with 40 parts of a solid acid-reacting substance like sodium bisulphite or tartaric acid or the free acid of an alkylated polynuclear hydrocarbon or sulfonic acid or an aromatic hydrocarbon.

115

The finished product is stable and when thrown into hot water, the oily substance separates from the hydrosulphite and the hydrosulphite combines with the solid acid and reacts with it to liberate hydrogen.

125

130

We have not attempted herein to specify or mention all possible substances that may be used or that will function to protect the hydrosulphite from deterioration, depending on the disclosures as made to describe the principle of the invention.

We claim:

1. A composition of matter that is stable under ordinary climatic conditions, consisting of a mixture of a stripping chemical of the hydrosulfite class and a salt of a saponified substance belonging to the class of oils, fats and waxes that will encase the individual particles of the stripping chemical and tend to exclude air and moisture therefrom.

2. A composition of matter that is stable under ordinary climatic conditions, consisting of a mixture of a stripping chemical of the hydrosulfite class and a salt of a saponified substance belonging to the class of oils, fats and waxes that will encase the individual particles of the stripping chemical and tend to exclude air and moisture therefrom and that will be released in an excess water solution and free the chemical so that it may enter into solution.

3. A composition of matter that is stable under ordinary climatic conditions consisting of a hydrosulphite salt and a salt of a saponified substance belonging to the class of oils, fats and waxes intimately mixed with said hydrosulphite and acting to envelope the particles thereof with a film.

4. A composition of matter that is stable under ordinary climatic conditions consisting of a hydrosulphite salt and a salt of a saponified substance belonging to the class of oils, fats and waxes intimately mixed with said hydrosulphite and acting to envelope the particles thereof with a film and that is capable of being released from the hydrosulphite in a water solution without interfering with the expected reaction of said solution after being released.

5. A composition of matter that is stable under ordinary climatic conditions, consisting of a mixture of a stripping chemical of the hydrosulfite class, and a salt of a saponified substance belonging to the class of oils, fats and waxes that will encase the individual particles of the stripping chemical and tend to exclude air and moisture therefrom and that will be released in an excess water solution and free the chemical so that it may enter into solution, and a substance that will assist in solidifying said composition.

6. A composition of matter consisting of a chemical of the hydrosulfite class and a salt of saponified substance belonging to the class of oils, fats and waxes intimately mixed therewith and acting to envelope the particles of the chemical and exclude air and moisture therefrom.

7. A composition of matter consisting of sodium hydrosulphite and a substantially

anhydrous salt of a sulfonated oil intimately mixed therewith and acting to envelope the particles of the chemical and exclude air and moisture therefrom.

8. A composition of matter consisting of sodium hydrosulphite, a substantially anhydrous salt of a sulfonated oil intimately mixed therewith and acting to envelope the particles of the chemical and exclude air and moisture therefrom, and anhydrous soda ash.

In testimony whereof we have affixed our signatures.

WOLF KRITCHEVSKY.
HAROLD C. PRUTSMAN.
